Primary Examiner — L. A. Grabenstetter(74) *Attorney, Agent, or Firm* — Antonio Ha & U.S. Patent, LLC(57) **CLAIM**

The ornamental design for a holder for a display panel, as shown and described.

DESCRIPTION

1. Holder for a display panel
 Fig. 1.1 illustrates a front perspective view of the subject design;
 Fig. 1.2 illustrates a rear perspective view of the subject design;
 Fig. 1.3 illustrates a bottom perspective view of the subject design;
 Fig. 1.4 illustrates a front view of the subject design;
 Fig. 1.5 illustrates a rear view of the subject design;
 Fig. 1.6 illustrates a left view of the subject design;
 Fig. 1.7 illustrates a right view of the subject design;
 Fig. 1.8 illustrates a top view of the subject design; and
 Fig. 1.9 illustrates a bottom view of the subject design.
 The broken lines, and regions surrounded on all sides by broken lines, depict portions of the holder for a display panel that form no part of the claimed design.

1 Claim, 9 Drawing Sheets(56)
